Patented Aug. 20, 1968

211,984

BASE FOR A DENTAL CHAIR OR THE LIKE

Arthur Gilbert Billin, Rochester, N.Y., assignor to Ritter
Pfaudler Corporation, Rochester, N.Y., a corporation of New York

Filed Mar. 21, 1967, Ser. No. 6,323

Term of patent 14 years

(Cl. D15—3)

FIG. 1

FIG. 2

FIG. 4

FIG. 1 is a side elevation view of my design for a dental chair base;

FIG. 2 is an enlarged bottom plan view of the base as shown in FIG. 1;

FIG. 3 is a top plan view of the base as shown in FIG. 2;

FIG. 4 is a perspective substantially front view of the dental chair base.

I claim:

The ornamental design for a base for a dental chair or the like, substantially as shown.
